UNITED STATES PATENT OFFICE.

JOHN GRAMELSPACHER, OF JASPER, INDIANA.

DESIGN FOR A DESK.

SPECIFICATION forming part of Design No. 26,813, dated March 23, 1897.

Application filed February 4, 1897. Serial No. 622,057. Term of patent 7 years.

To all whom it may concern:

Be it known that I, JOHN GRAMELSPACHER, a citizen of the United States, residing at Jasper, in the county of Dubois and State of Indiana, have invented a new and original Design for a Desk, (Case C,) of which the following is a specification.

This invention relates to a new and original design for a desk; and it has for its object to provide a design of this character that shall be both useful and ornamental.

The leading feature of the design resides in a desk having a main flat table supporting a cabinet-top provided with quadrantal end pieces and a roll-curtain connecting the curved front edges of said end pieces, a drawer-holding pedestal arranged at one end of the main table and provided at its upper end with a flat table-board disposed at one side of one of said quadrantal end pieces in a plane above the plane of the main table, and an upright rectangular cabinet supported on the rear top portion of the drawer-holding pedestal and projecting a distance above the plane of the cabinet-top of the main table.

A minor feature of the design resides in combining with the features above enumerated a rectangular drawer-space within the lower end of the upright rectangular cabinet supported on top of the drawer-holding pedestal, and also in providing this cabinet, between its lower drawer-space and flat horizontal top, with a rectangular front door having a correspondingly-shaped glass panel fitted in its front face.

The drawing is a perspective view of a desk embodying the herein-described design.

Referring to the accompanying drawing,

the numeral 1 designates the main flat rectangular table of the desk supporting a cabinet-top having opposite quadrantal end pieces 2, a roll-curtain 3, connecting the curved front edges of said end pieces, and an upright back portion formed with a plurality of pigeon-holes 4, certain of which holes are arranged in vertical columns extending downward to the upper surface of the table 1 and inclosing a squared open space 5, in the upper corners of which space are arranged angular drawers 6 of a somewhat triangular form.

A drawer-holding pedestal 7, containing a plurality of rectangular drawers 8, is located at one end of the main table 1 and is provided at its upper end with a flat table-board 9, disposed at one side of one of the quadrantal end pieces 2 in a plane above the plane of the table 1. An upright rectangular cabinet 10 is supported on the rear portion of the flat table-board 9 and is provided with a flat horizontal top 11 and a rectangular drawer-space 60 12 in its lower end. The cabinet 10 projects a distance above the plane of the cabinet-top of the main table 1 and is provided between its top 11 and drawer-space 12 with a rectangular front door 13, having a correspondingly-shaped glass panel 14 fitted in its front face.

What I claim is—

The design for a desk herein shown and described.

In testimony that I claim the foregoing as my own I have hereto affixed my signature in the presence of two witnesses.

JOHN GRAMELSPACHER.
